(57) **CLAIM**

The ornamental design for a face mill, as shown and described.

DESCRIPTION

FIG. 1 is a top perspective view of the face mill of a cutting tool assembly including the face mill, a fastener, and a tool holder;

FIG. 2 is a bottom perspective view of the face mill of FIG. 1;

FIG. 3 is a first side view of the face mill of FIG. 1;

FIG. 4 is a second side view of the face mill of FIG. 1;

FIG. 5 is a third side view of the face mill of FIG. 1;

FIG. 6 is a fourth side view of the face mill of FIG. 1;

FIG. 7 is a top view of the face mill of FIG. 1;

FIG. 8 is a bottom view of the face mill of FIG. 1;

FIG. 9 is a top perspective view of the face mill;

FIG. 10 is a bottom perspective view of the face mill of FIG. 9;

FIG. 11 is a first side view of the face mill of FIG. 9;

FIG. 12 is a second side view of the face mill of FIG. 9;

FIG. 13 is a third side view of the face mill of FIG. 9;

FIG. 14 is a fourth side view of the face mill of FIG. 9;

FIG. 15 is a top view of the face mill of FIG. 9; and,

FIG. 16 is a bottom view of the face mill of FIG. 9.

The broken lines of FIGS. 1-8 depict portions, or environment, of the face mill that form no part of the claimed design. The broken lines of FIGS. 9-16 depict portions of the face mill that form no part of the claimed design.

The dot-dot-dash lines depict boundary lines between claimed and unclaimed surfaces of the face mill.

The portions between the symbolic break lines in the drawings are broken away to indicate no particular arc length. The appearance of any portion of the article between the symbolic break lines shown in the figures forms no part of the claimed design.

1 Claim, 14 Drawing Sheets
